SOLVENT-EXTRACTION PROCESS AND APPARATUS

Michele Bonotto, Evansville, Ind., assignor to Extractol Process, Ltd., Wilmington, Del., a corporation of Delaware

Application August 12, 1939, Serial No. 289,791

11 Claims. (Cl. 202—39)

This invention relates to improvements in solvent-extraction processes and apparatus, and more particularly to processes and apparatus for the solvent-extraction of oil from oil-bearing materials.

Heretofore, solvent-extraction processes have generally been carried out by passing or moving, either by gravity or mechanical apparatus, a body or column of solid oil-bearing material through tanks of large diameter and subjecting such body or column to a liquid solvent moving in counter-current to the material through the entire body or column of material in the tank. Also, extraction has been carried out in a series of separate tubular conveyors arranged in inclined position by passing solvent in counter-current successively through each conveyor, but so far as I am aware, extraction has not been carried out by subjecting, in a single continuous conveyor, a long column of solid material to a series of separate counter-current extraction operations, such as hereinafter described.

I have found that counter-current extraction may be carried out in a single conduit-conveyor in which a relatively long and narrow column of material is being continuously conveyed if provision is made to overcome the friction encountered by the solvent in passing lengthwise through the moving material, and I have found that such friction may be overcome by providing means for causing or permitting the solvent to percolate at suitable intervals through the sides of the conduit-conveyor and the moving column of material to be extracted therein and applying successively such percolated solvent to other parts of the moving column or body of material. I have found that diffusion also may be accomplished in such a conveyor and that the process may thus comprise alternate stages of diffusion and leaching.

One of the objects of my invention is to enable the efficient extraction of oil or other soluble ingredients from material bearing such ingredients by the novel method of subjecting a column or body of such material in a single conduit to extraction by the alternate longitudinal passing of the solvent and the percolation thereof through the sides and preferably the provision in a single conveyor-conduit of a plurality of extraction sets of sections, each comprising at least one imperforate section for passing solvent longitudinally and one perforate section for percolating such solvent through the sides of the conveyor-conduit.

Another object of my invention is to enable the material to be subjected to alternate leach-

ing and diffusion in counter-current a plurality of times during conveyance through a single unit and preferably to subject to counter-current extraction a relatively long and narrow column of such material by alternate leaching and diffusion during conveyance thereof through a conveyor-conduit.

Another object of my invention is to enable such alternate leaching and diffusion operations to be carried out in a conventional conveyor during movement of the material and solvent in counter-current relationship.

Another object of my invention is to produce an extraction unit by utilizing a conventional conveyor-conduit having suitable liquid-passing conveyor elements by providing therein a plurality or series of imperforate portions arranged alternately with a plurality or series of perforated or screened portions surrounded by collecting or draining boxes, feeding solid material to be extracted to said conduit, conveying such material through said conduit including such screened sections, and subjecting such material to extraction by passing solvent through imperforate portions of said conduit and draining such solvent through said perforated portions.

Another object of my invention is to subject said material in such conveyor-conduit to alternate diffusion and leaching by feeding solvent liquid into said conduit through said imperforate portions in such quantities as to compensate for the quantity passing through said perforate portions into said draining boxes.

Another object of my invention is to produce an extraction unit by providing, in a conveyor-conduit at varying levels, groups of such alternate imperforate and perforate portions whereby solvent applied and enriched from material passing through one group may be reapplied to material in another group which is passing through a different stage of extraction.

Another object of my invention is to produce, in an alternately perforate and imperforate conduit of the type specified, a counter-current extraction unit by providing a plurality of such groups, applying and enriching fresh solvent in a group adjacent to the material outlet, draining such solvent and again applying such enriched solvent to a group closer to the material inlet or feed hopper.

Another object of my invention is to provide, along the length of a single conduit, a series of groups of such alternate perforate and imperforate portions, comprising a fresh-solvent group, a weak miscella group, and a strong-misella

group, and to apply the liquid drained from the fresh solvent group to the weak-miscella group and to apply the miscella drained from the weak-miscella group to the strong-miscella group.

Another object of my invention is to filter and simultaneously further enrich the strong miscella by filtering such strong miscella through fresh flaked material to deposit the fines from the miscella in the material and to remove and carry away in the filtrate free oil from such flaked material.

Another object of my invention is to produce an extraction unit by utilizing a conveyor conduit of sufficient length and providing therein a series of extraction groups, each embodying a plurality of cooperating section pairs, comprising a diffusion section composed of an imperforate conduit portion of given length and a leaching section also of given length composed of a perforate portion surrounded by a draining box, and providing conduits for solvent connected to inlets in the imperforate sections above said draining box, and applying through said conduits liquid solvent at a quantity or pressure regulated in accordance with the drainage to keep said diffusion sections under such conditions as to produce a diffusing action therein.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Fig. 1 is a view in side elevation of extraction apparatus embodying my invention;

Fig. 2 is a section on the line 2-2 of Fig. 1, looking in the direction of the arrows;

Fig. 3 is a view in perspective of a modified form of conveyor employed in extraction apparatus embodying my invention;

Fig. 4 is an illustrative diagrammatic view showing the pipes and tanks used in connection with the conveyor shown in Fig. 3;

Fig. 5 is still another modified form of my invention in which my conveyor extraction unit is employed in combination with an extraction column or tank.

Referring now to these drawings, I have illustrated three forms or types of apparatus suitable for carrying out my invention. Thus, in Figs. 1 and 2 I have illustrated a vertically-disposed flight-type conveyor having a material-incoming flight, an intermediate inclined flight and a material-outgoing flight. The incoming flight, as shown, comprises a vertical descending leg while the intermediate and outgoing flights comprise two upwardly and oppositely-inclined legs; in Figs. 3 and 4 I have shown a horizontally-disposed conveyor of rectangular conformation having incoming and outgoing flights and two intermediate flights which comprise four connected conveyor legs and in Fig. 5, I have shown a vertically disposed conveyor trapezoid-shaped in conformation having an incoming horizontal leg, an intermediate outwardly-inclined leg, an inwardly-inclined outgoing leg and a material-free descending leg which connects with the incoming horizontal leg which is fed from a column or tank such as described in my patents numbered 2,156,236 and 2,158,782.

Referring now particularly to Figs. 1 and 2 of these drawings, which constitute the preferred

form of mechanical apparatus for carrying out my invention, 1 indicates a vertically-disposed conveyor-conduit, triangular in elevation, which may embody any suitable type of material-conveying mechanism but preferably comprises a conveyor of the flight or drag-chain type. In the said preferred form of my invention, a conduit conveyor apparatus of generally-conventional construction has a casing 1^a which is suitably supported in conventional manner by members 1^b. A descending leg 2 constitutes the incoming flight and is connected and communicates with an intermediate upwardly and outwardly-inclined leg or flight 3 which is connected and 10 communicates with an outgoing flight 3' extending in upwardly-inclined, inwardly-disposed position and connected and communicating with the descending flight 2. This conveying mechanism thus comprises a continuous system of chain conveyor elements 4 connected together by chains 4^a and moved by drive wheel 5 driven by shaft 5' in conventional manner from any suitable source of power not shown.

The casing 1^a is composed of a series of portions connected together to provide liquid and vapor tight joints.

In said preferred form of apparatus, I provide, in each of the legs of the apparatus, an extraction group of alternate imperforate portions 7 and perforate portions 8 comprising a fresh solvent extraction group 9 positioned in the inclined material-outgoing leg, a used solvent group 10 in the intermediate inclined leg and a weak-miscella group 11 in the vertical material-incoming leg. Each of these groups contains a plurality or series of such imperforate and perforate portions, and in the preferred form of my process, each imperforate portion is provided with a liquid inlet conduit 12 and each perforate portion embodies a screen-wall portion 13 which is arranged flush with the casing 1^a and has surrounding said screen-wall portion an outside jacket 14 spaced from the screen-wall portion to provide a drain box between the said screen portion and said outside jacket.

In the preferred form of my invention, I preferably maintain the imperforate portion completely filled with solvent liquid so as to provide a diffusion section within the same, and these imperforate diffusion sections are alternated with leaching sections which comprise the screen-wall portions. The diffusion section may be kept full of liquid by applying through the inlet-conduits liquid solvent (comprising either pure solvent or used solvent which may be either strong or weak miscella or mixture) at a quantity or pressure regulated in accordance with the drainage through the screened leaching sections to keep the said diffusion section full of liquid and thus to enable a diffusing action to take place therein.

It will be understood that in oleaginous or oil-bearing materials, such as cotton seed, soya beans, tung nuts, linseed, castor beans, copra, bone meal, 65 meat scraps and the like, the oil constituents are contained in cells and the cells are surrounded by membranes or tissues and it has been found that when these oil-bearing materials are subjected to the action of a suitable solvent or diffusion agent under proper conditions, these membranes or films will act like permeable diaphragms to permit diffusion to take place between oil constituents and the solvent or diffusion agent. In other cases, such as the extraction of sugar from beets with water as a solvent, these mem-

branes will act like osmotic diaphragms to permit the osmotic discharge of the soluble constituents from the cells and in either case enabling the extraction of the soluble constituents from the cells and enabling osmotic discharge or diffusion and consequent extraction of the soluble constituents from the cells.

In order to promote the osmotic discharge or diffusion of soluble constituents through such membranes to the best possible advantage, the diffusion agent or solvent employed should be preferably applied to the material in counter-current, i. e., fresh solvent or diffusion agent having maximum strength should be applied to outgoing material from which a part of the solubles has theretofore been extracted and used solvent or diffusion agent of less strength should be applied to the fresh or incoming material and the diffusion agent or solvent should be thoroughly intermingled and kept in intimate contact with the mass of material for a time period sufficient to enable such osmotic action or diffusion to take place as distinguished from a mere washing operation. The determination of the length or duration of this time period will depend upon the type of material being treated, the condition of such material, the strength of the diffusion agent or solvent and other factors, such as the temperature maintained.

In the instant apparatus, it will be desirable, as hereinabove stated, to maintain the imperforate portion or diffusing section full of the diffusing agent or solvent and by so filling such imperforate section and then draining the solvent through a perforate leaching section below the diffusing section I am enabled, in a conveyor apparatus or conduit, to provide for a series of alternate diffusions in the imperforate sections and leachings in the perforate sections, such diffusion and leaching sections thus cooperating with each other in pairs.

I am enabled to produce counter-current relationship between the solvent liquid and the material by applying pure or fresh solvent having a maximum strength to the material passing through the extraction group 9 in the outgoing leg of the conveyor, then draining the relatively-strong used solvent from this extraction group through screens 13 into the draining boxes or jackets 14 and conducting this relatively-strong used solvent through pipe-portions 12' and applying it through inlet pipes 12 to the intermediate extraction group 10, then draining the twice used solvent from this intermediate group which has become what I shall term "relatively weak miscella", and applying this weak miscella to the incoming-material in group 11 in the descending leg 1' of the conveyor-conduit 1. As illustrated, pure solvent is pumped by pump 15^a from storage tank 15 to a pure solvent tank 15' located above the conduit-conveyor 1 to provide a suitable head. From this tank 15 the pure solvent is passed through a pipe 16, heater 17 and pipe 16' to branch inlet-conduits 18 which connect with individual or independent inlet-conduits 12 connected to inlets in the conveyor casing at diffusion sections or imperforate portions of said group 9 in the outgoing leg 1^c of said conveyor-conduit where an extraction operation comprising alternate diffusion and leaching takes place. The flow of extraction liquid through these pipes may be controlled or regulated by valves 12^a.

The used solvent from group 9 is drained

through screens 13, boxes 14, pipe portions 12' and conducted through inlet pipe portion 12 to imperforate diffusion sections of group 10 where further extraction operations of alternate diffusion and leaching take place. The used solvent from group 10 which has now become a mixture which I have termed "weak miscella" is drained through screens 13, jackets 14 and pipes 12^a, 12^b and 12^c to a weak-miscella tank 19 from which it is pumped by pump 20 through pipe 21, heater 22 and pipe 21' to and through inlet conduits 12 connected to the imperforate diffusion sections of group 11 which is located in the descending conveyor leg 1^a where fresh material in this incoming leg of the conveyor conduit is subjected to the solvent action of this relatively weak miscella.

The division of the process in three stages or groups 9, 10 and 11 is arbitrary and used only to better describe the apparatus. There is no such division in practical operation because the pure solvent becomes strong miscella by gradual enrichment in oil through a multiplicity of successive steps.

During passage through group 11, the relatively weak miscella is further enriched with oil and is drained through screens 13, jackets 14 and pipes 12^c and 12^d to a tank which I shall term a "strong miscella" tank 23.

The strong miscella, thus produced contains impurities in the form of particles of solids and in the preferred form of apparatus shown in Figs. 1 and 2, I filter this strong miscella through fresh material adjacent to the feed of the material by pumping this miscella by pump 24 and conducting same by pipe 25 through a filter section 26, comprising an imperforate section 27 having a liquid inlet 27' and draining sections 28 and 29 arranged on opposite sides of said inlet and having screen-portions 28' and 29' and jackets 28^a and 29^a, and thereafter draining the miscella through said jackets or draining boxes 28^a, 29^a and conducting the same by pipes 30, 30^a to a still, not shown.

It will be seen that I thus provide, in the descending leg or flight of the conveyor, a filtering section preferably extending to opposite sides of the miscella inlet 27' and that this filtering section, in this embodiment of my invention, comprises an imperforate percolating portion 27 and draining portions or boxes 28 and 29 one of which extends below an inlet and the other of which is positioned above the same. The solvent in this case is fed through the inlet to provide, within the imperforate portion, a percolating action so as to cause the solid material to function as a filtering bed. Assuming that flaked soy-beans are fed through the material feed hopper 31 and moderately packed within the filtering section 26 and particularly within the imperforate portion, the soy-bean flakes will serve as an efficient filtering agent or filter bed and when miscella is percolated therethrough at a suitable constant pressure and by a suitable proper hydrostatic head or pump pressure, the liquid miscella will pass through the soy-bean flakes in the said descending leg of the casing and percolate, leaving in the interstices of the packed soy-bean flakes, the fine particles of solid material which had been in suspension in the miscella. As the deposit of the fines in the interstices of the soy-bean flakes in the conveyor section increases, the miscella will encounter more resistance and if a hydrostatic head is em-

ployed the length of that hydrostatic head may be increased in proportion to the resistance to the flow until preferably the optimum pressure to which the liquid should be subjected is reached.

This filter section is not per se a part of my present invention though the extraction apparatus hereinabove described provides a convenient and cooperative apparatus wherein I may employ a single flow of material for both the extraction and filtering operations, and within which the operation of filtering may be carried on without the necessity of providing any special apparatus therefor. The filtering operation is accomplished with fresh solid material and the feed of solvent is so regulated as to produce within the imperforate portion of the filtering section a percolating action instead of a diffusion action, and such filtering operation may be carried on at any suitable position in a conveyor of the type hereinabove specified.

When a filtering action of the type specified is utilized in combination with the extraction apparatus hereinabove described, the liquid miscella to be filtered will be fed through the leg of the conveyor-casing into which the feed of solid material is delivered, and will, as aforesaid, percolate, leaving in the interstices of the packed flaked material the fine particles of solid material which had been in suspension in the miscella. The flaked material so loaded will then, in the same continuous conveying movement, be immediately conveyed to and through the extraction or alternate diffusion and leaching sections of my apparatus.

Obviously, as the feeding process of solid material through the hopper continues, the whole column of fresh flaked material will be forced through the filtering section and the fresh material will serve as a filter bed in said section and, as the particles are heavily deposited, the material will be displaced and a new continuously-moving filter bed of such material will pass into place, and a new coat of fines will be deposited in the interstices. In the apparatus shown, the fines deposited move downwardly. Consequently, the path or line of least resistance for the miscella will be upwardly, but a relatively small amount of liquid will, under pressure percolate downwardly through the downwardly-moving material to a level below the miscella feed conduit to the perforated drainage section 29 while the main body of miscella liquid from the miscella feed conduit will follow the line of least resistance and move upwardly at a more rapid rate than that of the material toward the upper screen draining or outlet section where it will pass through the perforations of the screened portion and into the drainage box 28. Miscella from both boxes is conducted through the pipes 28' and 29' to a still or to a suitable storage tank not shown. In some cases the perforate drainage section 29 may be omitted.

It will be obvious that the oil-bearing filtering material, after miscella has passed through it, will be soaked with solvent and oil and will contain fine particles of the material in process, all of which are valuable, and that such solvent and oil as well as the oil-bearing fine particles will be automatically recovered in further processing in the extraction section. On the other hand, the miscella will be further enriched because it will dissolve the free oil contained in the flakes and

this will provide a further separate economy in the distilling step of the extraction process.

After the travel of the material through the diffusion agent or solvent, as hereinabove described, said material is preferably passed through an elongated draining section 14, the drained liquid from which is passed through the pipe 12' into pipe 12 where it joins the solvent coming from the adjacent drain or percolating box 10 of the group 9. The percolated or drained material is then conveyed to a spout 16 and dropped by gravity into one of a group of dryers D and D'.

Owing to the fact that vapors passing from the dryers to the condensers always carry fine dust which impairs the efficiency of the condensers, it has been the practice in the art to interpose, between the dryers and the condensers, dust collectors of some type. In accordance with my invention, I avoid and eliminate such dust collectors. Thus, as shown, particularly in Figs. 1 and 3 to 5, I force the solvent vapors bearing dust through a layer of material LM. This is accomplished by positioning the vapor-outlet conduit 11' in relation to the discharge conduit 16' and so as to provide an imperforate conveyor section 7a between such material discharge and said vapor outlet conduit. It will thus be seen that the vapors arising from the dryer are compelled to pass through a continuously-moving layer of solid material LM to reach the vapor outlet conduit 11' from which they pass to a suitable condenser C. In order to force the vapors to traverse the extraction material layer to the condenser, a seal should be built up in the spout or hopper 31 adjacent to the material inlet and in the embodiment illustrated, such a seal is produced by providing, in the spout or hopper 31, a suitable depth of material which is continuously and at all times kept full of material. Such arrangement will also cause a condensation of solvent vapors in the material entering the extractor through the hopper 31 resulting in pre-heating the material and soaking it with solvent as it enters the extractor. In case the material to be extracted is flaked or prepared under hot conditions, a conventional star feeder or an air-lock positioned between the hopper and the extractor will provide the necessary seal.

In certain forms of dryers commonly used, the solvent vapors are, in such dryers, superheated and when dryer devices of this type are employed in conjunction with my apparatus, a part of the superheated vapors will, by passing through the material layer LM, preheat the material just prior to its passage to the spout 31 and before the same enters the dryers.

Some solid materials will be more suitable than others for extraction in my aforesaid apparatus. The spacing of the percolating or draining boxes 60 and the consequent length of the imperforate sections through which the solvent must pass will depend upon the characteristics of the material to be extracted. The coarser the material the less friction there will be and consequently the spacing of the percolating or draining boxes will be further apart and the imperforate diffusing sections will be longer. Theoretically, if it were possible to have a material which offered no resistance to a counter-current flow of the solvent in a conveyor of the type specified arranged as in Fig. 1, there would be no need of percolating boxes but, inasmuch as that theoretical possibility does not exist, my provision of percolating 65 or draining boxes is designed to overcome the

friction which is encountered to compel the solvent to circulate in counter-current.

It will be understood that if a solvent of high specific gravity is employed so that the material has a tendency to float, my apparatus will be equally suited to extract with such solvent.

In Figs. 3 and 4 I have shown a horizontally-disposed construction embodying another application or modification of my invention. In this embodiment of my invention, the solid material is fed continuously through hopper 32 and through a material inlet or feed hopper 32 into a horizontally-disposed conveyor 33 which is of conventional type except for application thereto of the draining boxes and the solvent conducting pipes. In Figs. 3 and 4, the percolating sections 34 and 35 and the imperforate section 36 constitute a filtering section such as hereinabove described, while the remaining draining boxes connected with the conveyor constitute a series of extraction units which are arranged in diffusion and leaching groups, which as illustrated, comprise groups of three draining boxes or leaching sections 37, 38 and 50 spaced from each other to provide therebetween imperforate portions or diffusion sections 40, 41. Referring to Fig. 4, pure solvent is fed from a tank 42 through pipe 42' to inlet conduits 43, 43' which are connected with the imperforate portions or diffusion sections 40 and 41. Used solvent is drained from draining boxes 37 and 38 through the pipe 44 into tank 45 from which it is pumped by pump 46 through conduit 47 and through inlet branch conduits 47', 47'' to the next imperforate sections 48 and 49 positioned adjacent to the boxes 50 and 51. Miscella is drained from boxes 50 and 51 through pipes 52, 52' to the tank 45' and thence by pump 46' to the next set or group of extraction boxes until the solvent in its counter-current movement to the movement of the material reaches the spaced filter boxes 34 and 35 having the imperforate filter section 36. The filter boxes 34 and 35 are drained through pipes 34', 35' and 36' and conducted to a miscella storage tank or still not shown. In other respects this construction is similar to that hereinabove shown and described in relation to Figs. 1 and 2.

In Fig. 5, I have shown a modified embodiment of my invention in which an extraction column or tank is combined with the conduit-conveyor extraction apparatus of my present invention which, it will be seen, will have the double function of conveying the process material from the extraction column or tank to the dryers and simultaneously extracting soluble ingredients therefrom. One of the advantages of this new combination is that the extraction column or tank of my former patents may be substantially reduced in length or height. A combination of this type, however, will be principally useful in the extraction of materials which mainly require a process of washing or leaching as distinguished from such materials as vegetable seeds which require washing or leaching and diffusion.

In the apparatus of Fig. 5, the material to be extracted is fed through hopper 55 and screw-conveyor-conduit 56 to a vertically-disposed extraction tank 57, which may be of my known type, but which preferably, as shown, is of the type illustrated and fully described in my Patents Nos. 2,156,236 and 2,158,782. The said material fed through the hopper is passed through a process of solvent extraction in the tank and then conducted through an outlet 57' in the bottom

of the tank to a horizontal leg 58' of a conventional conveyor-conduit 58 having additional legs 58^a and 58^b extending above the tank 57 and having a discharge connection or outlet chute 59 connected with one of a series of three dryers 60, 60', 60'', from which the material may be delivered to additional solvent-eliminating apparatus or to a storage bin. The conveyor, as shown, is of the chain type and has a continuous connecting upper part 58^c, a descending empty leg 58^d and a connecting lower part 58^e, the entire conveyor being constructed in well-known vapor-tight sections and being supported by members 61, 61', 61'' and wheel 62 journaled on shaft 62' rotated from any suitable source of power not shown, to move the chain of conveyors.

In the ascending leg 58^b of the conveyor above the liquid-level 57^a in extraction column or tank 57, I provide a group or series of alternate imperforate and perforate sections 63 and 64, the latter of which is surrounded by liquid-draining boxes 65 similar in all respects to the draining boxes hereinabove described.

In the instant embodiment of my invention, pure or fresh solvent is fed from tank 66 through conduit 67, heater 68 and conduit 67' into the leg 58^b of the conveyor 58 at the upper part thereof and is caused to percolate downwardly through the upwardly-moving material in the conveyor. As illustrated, solvent enters the conduit at the imperforate section 63 between the upper boxes 65 and is drained from these boxes and from the draining section 69 and conducted to a lower imperforate section in substantially the manner hereinabove described in relation to Fig. 1 until the solvent reaches the lowermost group of boxes which drain into pipe 70 which conducts the solvent to the empty descending leg 58^d above the solvent level 71 in the conveyor. The used solvent, therefore, passes through this descending leg and up through the material outlet opening 57' into the extraction tank 57 in counter-current with the material. After passage through the tank, the used solvent or miscella passes out through pipes 72 to a filter if necessary, and then to a distiller.

It will be seen, therefore, that the material and solvent, both in the tank 57 and in the conveyor leg 58^b move in counter-current relationship; that I have provided in the lower portion of the conveyor a suitable head of liquid for forcing passage thereof through the tank, and that I have, in the conveyor, provided the draining boxes and connecting pipes to overcome the friction encountered by the solvent in passing through the material, as hereinabove more particularly described.

The operation of the various extraction units will be apparent to those skilled in the art from the above description.

It will be obvious also that in the apparatus shown in Fig. 5, the conveying movement of the material and the flow of the solvent passed through the inlet conduit 67' may be suitably regulated in relation to the quantity of solvent percolating through the perforations of the perforated portions to produce a washing or leaching action in the imperforate sections of the leg 58^b as well as in the perforate sections. This may be accomplished by so regulating the quantity and pressure of the ingoing solvent in relation to the quantity being drained as to keep solvent continuously flowing through the imperforate sections at a suitable rate without any filling of such imperforate sections. A valve 67^a may be

used to regulate the flow of the solvent from the tank 66. Obviously, by similar regulation of the regulating valves in the embodiments of my invention shown in Figs. 1-4, the quantity of solvent percolated may also be controlled so as to produce a washing or leaching action in the imperforate sections as well as in the perforate sections.

Having described my invention, I claim:

1. Counter-current solvent-extraction apparatus embodying, in combination, a conduit-conveyor comprising a liquid and vapor tight conduit and liquid-passing conveyor members movable therethrough and adapted to carry solid material to be extracted, said conduit having material feed-inlet and discharge openings and being provided, between said inlet and discharge openings, with a plurality of perforate wall sections arranged to cooperate with imperforate wall sections of the conduit to provide extraction sets, each set including at least one perforate and one imperforate section and having a solvent-inlet pipe connected thereto, means for draining solvent from the perforate section, said conduit-conveyor being of the continuous chain type having a plurality of legs and each leg being provided with a group of extraction sets arranged in successive relationship along the length of the leg, means for conducting fresh solvent to the group in the leg nearest to the material discharge opening, and means for conducting enriched solvent from said last-mentioned group to a group nearer the material feed inlet, whereby the solvent and material will be moved in counter-current relationship.

2. Counter-current solvent-extraction apparatus embodying, in combination, a conduit-conveyor comprising a liquid and vapor tight conduit and liquid-passing conveyor members movable therethrough and adapted to carry solid material to be extracted, said conduit having material feed-inlet and discharge openings and being provided, between said inlet and discharge openings, with a plurality of perforate wall sections arranged to cooperate with imperforate wall sections of the conduit to provide extraction sets, each set including at least one perforate and one imperforate section and having a solvent-inlet pipe connected thereto, means for draining solvent from the perforate section, said conduit-conveyor being of the continuous chain type having a material-feed leg, an intermediate leg and a material discharge leg, each leg being provided with a group of extraction sets arranged in successive relationship along the length of the leg, and means for conducting fresh solvent to the group in the material-discharge leg, and means for successively conducting enriched solvent from said group in the material feed leg to the group in the intermediate leg and from said intermediate leg group to the material-feed group, whereby the solvent and material will be moved in counter-current relationship.

3. Counter-current solvent-extraction apparatus embodying, in combination, a conduit-conveyor comprising a liquid and vapor tight conduit and liquid-passing conveyor members movable therethrough and adapted to carry solid material to be extracted, said conduit having material feed-inlet and discharge openings, and being provided, between said inlet and discharge openings, with a plurality of perforate wall sections arranged to cooperate with imperforate wall sections of the conduit to provide extraction sets, each set including at least one perforate and

one imperforate section and having a solvent-inlet pipe connected thereto, means for draining solvent from the perforate section, said conduit-conveyor having a dryer connected with the material-discharge opening, a vapor-outlet conduit positioned adjacent to but separated from the said material discharge opening by a charged section of the conveyor, whereby vapors from the dryer are filtered through the solid material on their way to the vapor outlet.

4. Solvent-extraction apparatus embodying, in combination, a vapor and liquid-tight conveyor-extractor casing and conveyor members adapted to convey solid material and to pass liquid movable through said casing, a dryer, a vapor-tight, connection between the discharge end of said conveyor-extractor and the dryer to discharge extracted material from the conveyor-extractor in said dryer, and an outlet in the conveyor-extractor casing removed from said connection to cause solvent vapors coming from said dryer to traverse a bed of extracted material in the conveyor-extractor to filter said vapors.

5. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent through an inlet in each of said zones of said body of solid material during movement thereof, regulating the rate of flow of said liquid-solvent to flood said zones, and withdrawing used solvent from said zones through said outlets.

6. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent in a sidewise direction through an inlet in each of said zones of said body of solid material during movement, regulating the rate of flow of said liquid-solvent to overcome the normal friction of the material encountered by the solvent, to compensate for the velocity of movement of such material and to provide for a flooding of said zones, and withdrawing used solvent from said zones through said outlets.

7. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by pro-

viding solvent outlets that divide said columnar body into a plurality of treating zones, passing liquid-solvent in a sidewise direction through an inlet in each of said zones of said body of solid material during movement thereof, regulating the rate of flow of the solvent to overcome the normal friction of the material encountered by the solvent, to compensate for the velocity of movement of such material and to provide for a flooding of said zones and an overflow at opposite ends thereof, and withdrawing used solvent through solvent outlets at opposite ends of each of said zones.

8. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent in a sidewise direction through an inlet in each of said zones of said body of solid material during movement thereof, regulating the rate of flow of said liquid-solvent to flood said zones by overcoming the normal friction of the material encountered by the solvent, withdrawing used solvent from said zones through said outlets, and applying the used solvent withdrawn from one zone to a successive extraction zone in counter-current relationship to the movement of the solid material.

9. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent in a sidewise direction through an inlet in each of said zones of said body of solid material during movement thereof, regulating the rate of flow of said liquid-solvent to flood said zones by overcoming the normal friction of the material encountered by the solvent and compensating for the velocity of movement thereof, withdrawing used solvent from said zones through said outlets, applying the used solvent withdrawn from one zone to a successive extraction zone in counter-current relation-

ship to the movement of the solid material, and repeating said process a plurality of times to subject the same moving column of material to a plurality of alternate stages of diffusion and leaching.

10. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent in a sidewise direction through an inlet in each of said zones of said body of solid material during movement thereof, regulating the rate of flow of the solvent to overcome the normal friction of the material encountered by the solvent, to compensate for the velocity of movement of such material and to provide for a flooding of said zones and an overflow at opposite ends thereof, withdrawing used solvent through solvent outlets at opposite ends of each of said zones, and applying the used solvent withdrawn from one zone to a successive extraction zone in counter-current relationship to the movement of the solid material.

11. A process of continuous solvent extraction of oil-bearing solid materials consisting in providing a continuous conduit-conveyor, feeding to and continuously moving solid material through said conduit-conveyor while maintaining the same in substantially filled condition to produce, in said conduit-conveyor, a columnar body of solid material having a given amount of frictional resistance to the flow of liquid-solvent, dividing, into a plurality of units, the total amount of friction in said columnar body by providing solvent outlets that divide said columnar body into a plurality of treating zones, passing liquid-solvent in a sidewise direction through an inlet in each of said zones of said body of solid material during movement thereof, regulating the rate of flow of the solvent to overcome the normal friction of the material encountered by the solvent, to compensate for the velocity of movement of such material and to provide for a flooding of said zones and an overflow at opposite ends thereof, withdrawing used solvent through solvent outlets at opposite ends of each of said zones, and repeating said process a plurality of times to subject the same moving column of material to a plurality of alternate stages of diffusion and leaching.

MICHELE BONOTTO.
